BEER CAN

Karl William Koch III, 39 Crescent Road,
Port Washington, N.Y. 11050

Filed Feb. 27, 1968, Ser. No. 10,740

Term of patent 14 years

Int. Cl. D9—07

U.S. Cl. D9—195

The figure is a perspective view of a beer can showing my new design.

The dominant features of my design reside in the portions shown in full lines.

The can is circular in all cross sections and the side opposite that shown is the same in appearance as the side shown except that the label area is replaced by a continuation of the barrel motif.

I claim:

The ornamental design for a beer can, substantially as shown and described.
